UNITED STATES PATENT OFFICE.

ADOLPH G. KAUFMAN, OF NEW YORK, N. Y.

GENERATOR.

1,370,591.

Specification of Letters Patent.

Patented Mar. 8, 1921.

Application filed November 19, 1919. Serial No. 339,159.

To all whom it may concern:

Be it known that I, ADOLPH G. KAUFMAN, a citizen of the United States, residing at New York, in the county and State of New

5 York, have invented a new and useful Generator, of which the following is a specification.

This invention relates to incandescent lamps where the hydrocarbon fluid is vaporized and burned in connection with one, or 10 more incandescent mantles—preferably two; and the drawing shows a burner head adapted to utilize two mantles for lighting purposes. The object of my invention is to provide 15 a generator, or vaporizer in which the hydrocarbon fluid will be converted into gas so constructed that a match can be used in an efficient manner for starting purposes; a further object of my invention is to provide 20 a generator so constructed that the generator and coil can be rotated without breaking the mantle, or mantles of the lamp; to provide an increased heating portion without danger of the formation of carbon; and 25 to provide a generator with strainers so constructed and inserted that the hydrocarbon fluid will not be retained in the coil.

The invention is illustrated in the accompanying drawing, in which—

30 Figure 1, is an elevation of a burner head of a lamp, and of my improved generator applied thereto—parts being broken away to show the construction;

Fig. 2, is a plan view of the generator;

35 Fig. 3, is an enlarged view of the top part of the generator, showing one form of attaching the head; and,

Fig. 4, is a plan view of a modified form of generator.

40 In the drawing like numerals of reference refer to the same parts in each of the views.

In practice I provide a generator 5, with a coil 6, formed without the zone of the mantles 7. In the drawing but one mantle 7 is 45 shown, but the lamp head has the usual mixing chamber 9, and two burner tubes 10 and 11, so that two mantles 7 will be employed, suspended below the air intake 8, and adjacent to the coil 6 so that the heat of the

50 mantles, in incandescence, will be radiated directly upon the coil, and yet the coil will be free to rotate in removing the generator without possibility of breaking the mantles with the coil, as will be clear. The burner head, it will be observed, is not supported by the generator; but is wholly supported by

the single standard 12, which may have an extension 13, on which the shade holder 14 is adjustably mounted in a reversible manner, as will be clear. 60

In practice I prefer to mount on the top of the generator a removable nozzle 15, as more particularly shown in Fig. 3. The nozzle 15, may be mounted in a nut 16, fastened on the generator 5, or the nozzle may 65 be secured on the generator in any desired manner, as the method by which the nozzle is secured to the generator forms no part of my present invention. The desirable feature of my invention, however, lies in the 70 fact that the nozzle 15 will fit in the orifice 17 in the manner shown in Fig. 1, to leave the space 18 between the nut, or head 16, and the bottom of the air intake 8. By having this nozzle fit in the orifice, as described, 75 the generator 5 may be very small in diameter while the nozzle will fill the orifice in the burner head adapted to receive an ordinary generator, or a generator, or vaporizer of any construction. 80

By having the space 18, and the nut, forming the head, or stop, as shown, the generator can never be raised a sufficient distance to bring the coil 6 into contact with the mantles 7. Thus the head, or nut 16 forms 85 a stop to limit the raising of the generator, as will be clear.

In practice I prefer to mount a preheating cup 19 on the generator, so that in starting the lamp a preheating fluid may be placed in 90 this cup in the ordinary manner in starting the lamp, or a match can be used for this purpose.

Where a match is used for starting the lamp it is designed to have the coil 6 sufficiently close to the cup 19 that a match 20 will rest within the coil 6 and engage the cup 19, as shown, so that the cup will form the rest for the match. Thus, in burning, the flame of the match will ascend, as will be understood, and generate sufficient heat to start the lamp thereby enabling the lamp to be started with a less number of matches than would be necessary with the coil in a different position. 95 100 105

It will be understood that the cup 19 need not be used for the purpose of supporting the match, as any ledge, or projection placed adjacent to the coil 6 on which the match might rest in burning would answer the purpose of assisting the coil 6 in supporting the match during combustion. It will be under- 110

stood, also, that since the coil is disposed in a horizontal manner, a match might be rested on the same in burning, as shown in dotted lines in Fig. 1. By making the coil 5 horizontal the vaporization of the hydrocarbon fluid will be accelerated, as will be understood, by reason of the fact that the bend 21, lies adjacent to the bend 22 just below the coil, so that the ascending fluid to 10 be vaporized will be in a position to receive the heat from the match in starting. After starting, the heat of incandescence of the mantles will readily generate the vapor in the part 23 of the generator; and this action 15 will be more certain by reason of the fact that the coil 6 lies within the heat zone of the mantles so that the hydrocarbon fluid in ascending will be heated within the coil before reaching the part 23. In practice I prefer 20 to mount a strainer 24 in the part 23 of the generator, and may also mount a strainer 25 in the lower, or part 26 of the generator. It will be noticed that neither of these strainers extend into the coil 6 so that there 25 is a clear passageway 27 within the coil in which the hydrocarbon fluid may lie after passing through the lower strainer, or upward from the font, not shown, to the part 23 of the generator where it is converted 30 into gas for commingling with air and combustion.

It will be understood that I may use any method of construction that may be desired for the purpose of removing, and inserting 35 the strainer, or strainers, without departing from the spirit of my invention. In practice it is desirable to keep the generator clean; and this necessitates the removal of the strainers in many cases. It is desirable, 40 therefore, to provide a strainer, and a construction by which the removal and renewal can be accomplished readily, and with the loss of as little time as possible. Consequently, as the necessity is so urgent, any 45 desired construction may be employed; and it is not thought necessary to illustrate the various methods.

By using two mantles I bring each mantle 50 into close contact with the coil 6; and by making the coil 6 in the preferred form, as shown specially in Fig. 2, the coils 28, will bring the fluid into close contact with each mantle, as will be understood.

In Fig. 4 I have shown a coil 6' of different construction than shown in Fig. 2, in 55 which the generator is not crossed. A generator constructed in this way will work successfully, but is not as desirable as the construction shown in Fig. 2. In this construction I have shown the preheating cup 19' on the generator.

Where the cup is used, I prefer to fix it 60 on the generator so the generator can be rotated with this cup instead of having to use a tool. As stated above, the generator can

also be rotated by grasping the coil 6; and this would be true whether a coil, as shown in Fig. 2, or a coil as shown in Fig. 4 is used. If the coil shown in Fig. 4 is used it should be located sufficiently close to the cup 19' so 70 a match could be used, as described above. If the coil shown in Fig. 4 is used, I prefer to bend the part 29 as shown, and thereby form the loops 28' in the coil.

In operation, the hydrocarbon fluid, as 75 gasolene, or kerosene is fed to the generator through the burner valve 30. As the fluid ascends it is strained through the strainer 25 after which it fills the coil 6, and lies there till ready to be taken up by the part 23. In 80 starting the lamp the flame of the match will supply the heat to start the initial vaporization. Owing to the construction of the generator usually one match will be sufficient to generate sufficient gas to start the 85 lamp. If not, another match can be readily lighted and placed in position for starting purposes. When the lamp is started, the heat of the mantles will generate the gas in the part 23 of the generator, while the 90 radiant heat of the mantles will descend and warm up the hydrocarbon fluid within the coil 6 without any danger whatever of forming carbon within this coil.

I have not shown any method of fixing 95 the preheating cup on the generator, or of mounting the shade holder on the single standard, nor other features of construction. My invention lies in the formation of the generator tube, as described above so the 100 generator can be removed without any danger whatever of breaking the mantles; and this is a very important feature since it is generally necessary to frequently remove the generator for the purpose of cleaning, 105 or "needling" the discharge orifice in the generator nozzle; and it would be a serious matter, and add much to the cost of operation of the lamp if the mantles were broken each time it was necessary to remove the 110 generator.

I know that coils have been used in the generator; but believe I have made a substantial improvement in so locating the coil that it will form a part of the match holding 115 means, and also in that the coil lies wholly without the zone of the mantles.

The construction is simple in operation; and efficient in use.

I claim:

1. In an incandescent light, a plurality of suspended mantles, a generator having a portion thereof between the mantles and having a horizontal coil outside of the zone of the mantle whereby the generator can be 125 rotated without breaking the mantle.

2. In an incandescent light, a plurality of suspended mantles, a generator having a portion thereof between the mantles and having a horizontal coil outside the zone of 130

the mantles but lying within the heat zone thereof whereby the generator can be rotated without breaking the mantles.

3. In an incandescent light, a generator having a horizontal coil therein outside and below the zone of the mantles, in combination with a preheating cup mounted on the generator adjacent to said coil whereby a match may be supported jointly by said 10 coil and preheating cup, for the purpose set forth.

4. In an incandescent light, a generator having a horizontal coil outside and below the zone of the mantles, and a stop adapted 15 to limit the vertical upward movement of the generator whereby said coil is prevented entering the zone of the mantles.

5. In an incandescent light having an orifice adapted to receive the nozzle of a generator, a generator having a horizontal coil therein outside and below the zone of the mantles, and a stop adjacent to the top of 20 the generator adapted to limit the entrance

of the generator in said orifice whereby said coil is prevented entering the zone of the 25 mantles.

6. In an incandescent light, a generator having a horizontal coil therein outside and below the zone of the mantles, and having a nozzle mounted on the top thereof larger 30 in diameter than the generator and adapted to limit the vertical movement of the generator whereby said coil is prevented entering the zone of the mantles.

7. In an incandescent light, a generator 35 having a horizontal coil therein outside and below the zone of the mantles, and having a nozzle mounted thereon, a burner head having an orifice adapted to receive said nozzle, said nozzle having a stop adapted to 40 limit its entrance in said orifice whereby said coil is prevented entering the zone of the mantles.

Dated November 18th, 1919.

ADOLPH G. KAUFMAN.
